Wm. Stewart

CHARLES B. LOVELESS, OF SYRACUSE, NEW YORK.

Letters Patent No. 87,271, dated February 23, 1869.

IMPROVED PORTABLE GAS-GENERATOR

The Schedule referred to in these Letters Patent and making part of the same.

To all whom it may concern:

Be it known that I, CHARLES B. LOVELESS, of Syracuse, in the county of Onondaga, and in the State of New York, have invented new and useful Improvements in Machines for Generating Hydrocarbon-Gas; and I do hereby declare that the following is a full, clear, and exact description thereof, reference being had to the accompanying drawings, and to the letters of reference marked thereon, in which—

Figure 1 is a side elevation, and

Figure 2 is a sectional view of my invention.

Figure 3 is a plan view of the stuffing-box B.

The nature of my invention consists in the improved means of supporting the cylinder which contains the zinc in the portable gas-generator patented to me.

To enable others skilled in the art to make and use my invention, I will describe its construction and operation.

A is the rod, by means of which the cylinder C, containing the zinc, is lowered into the sulphuric acid S, when it is desirable to operate the machine, or the means by which the cylinder C is raised out of acid when it is desired to stop the operation of the machine. The rod A has a knob, α , by which it is more conveniently operated.

The stuffing-box B has a thread cut on its inside, at its lower end, to fit the thread on tube H.

In the stuffing-box B, a recess, of ample and conven-

ient size, is made, to receive stuffing or packing D, which is composed of rubber, leather, or other suitable material, and which compresses the rod A so tightly as to hold it, with cylinder C, with which it is connected, at any desired height.

The tightness of the hold of the packing D on the rod A, can be, in part, regulated by screwing or unscrewing packing-box B on or from tube H.

The advantages of my improvement, over other means for stopping or starting portable gas generators, are seen in the simplicity, effectiveness, and convenience of construction.

Having thus fully described my invention,

What I claim as new, and desire to secure by Letters Patent, is—

The combination of the packing-box B, packing D, and rod A, with the adjustable cylinder C, when used in a gas-generator, constructed substantially as described, and operating as and for the purposes set forth.

In testimony that I claim the above-described new and useful improvements in hydrocarbon-gas machines, I have hereunto signed my name, this 4th day of January, 1869.

CHARLES B. LOVELESS.
